UNITED STATES PATENT OFFICE.

LUCIUS A. SMITH AND CLEMENT SMITH, OF TOPEKA, KANSAS.

TRUSS.

SPECIFICATION forming part of Letters Patent No. 638,365, dated December 5, 1899.

Application filed February 4, 1898. Serial No. 669,144. (No model.)

To all whom it may concern:

Be it known that we, LUCIUS A. SMITH and CLEMENT SMITH, citizens of the United States, residing at Topeka, in the county of Shawnee 5 and State of Kansas, have invented new and useful Improvements in Trusses, of which the following is a specification.

Our invention relates to trusses, and more particularly to means for fastening the pad-bodies of trusses upon patients.

Heretofore the great difference in the body measurements of persons afflicted with hernia and kindred diseases has compelled dealers to keep a large number of trusses with belts 15 of different lengths on hand in order to be able to fit any patient who might present himself. The belts are ordinarily formed of elastic material, which is liable to deteriorate in time and become worthless, and consequently 20 the necessity of keeping a large number of trusses in stock occasions the dealer a considerable loss.

Our invention seeks to obviate the necessity of a dealer keeping a large number of trusses with belts of various lengths in stock by providing the truss at the time of manufacture with a belt sufficiently long to meet any ordinary requirement and connecting such belt with the pad-body of the truss in 25 such a manner that when too long it may be disconnected from the pad-body and cut to reduce its length to the extent desired and may then be again readily connected with the pad-body in such a manner that its rough-cut 30 end will be hidden from view and prevented from detracting from the finish of the truss and also prevented from curling and pressing the clothing of the patient outwardly and its opposite end will be left free for detachable 35 connection with the pad-body.

Other objects and advantages of the invention will be fully understood from the following description and claims when taken in conjunction with the annexed drawings, in 40 which—

Figure 1 is a perspective view of a single truss embodying our invention. Figs. 2, 3, and 4 are enlarged detail sections taken in the planes indicated by the lines ww , xx , and yy , respectively, of Fig. 1. Fig. 5 is a perspective view illustrating the male clasp member at one end of the belt; and Fig. 6 is

a detail elevation of a portion of a double truss—*i. e.*, one having two pads—embodying our invention.

55

Referring by letter to the said drawings, and more particularly to Figs. 1 to 5 thereof, A designates the pad-body or pad-holding body of a single truss—*i. e.*, one having but a single pad—and B designates the belt thereof, 60 which may be formed of any material, although that which is elastic is preferred, and is designed to surround the body of a patient after the well-known manner. One end of this belt is detachably connected with the 65 pad-holding body, so as to enable a patient to readily put on and take off the truss, such connection being preferably effected by a clasp C. (Better illustrated in Figs. 1, 2, and 5.) This clasp C comprises male and female members, the male member a being carried by a tab b at the end of the belt and having a loop 70 c and a T-shaped tongue d disposed at an angle to the loop and the female member e being connected to the face of the pad-body. 75 Said female member has a central depressed portion f for the passage of a screw g and a marginal flange h , and it is also provided in its portion i , which is set out from the face of the pad-holding body, with three (more or less) slots j , arranged about as shown in Fig. 1. One of these slots is designed to receive the T-shaped tongue d of the member a , while the other two are designed to receive the tongue of a similar member k on the ordinary 80 under strap l , so as to permit of the truss being used as a right and left hand truss, as desired. It will be appreciated from the foregoing that the construction of the clasp permits of one end of the belt being readily connected to or disconnected from the pad-body, 85 and this without liability of the said end of the belt becoming casually disconnected from the pad-holding body; also, that the construction of the clasp is such that no obstructions are afforded to catch into the clothing 90 of the patient.

The pad-holding body A is provided with a pocket D, which may be and preferably is formed of the leather or other material covering the outer side of the pad-holding body and has its mouth or open end remote from the clasp member e , as shown. Said pad-body A is also provided on its face at a point ad-

jacent to the mouth of the pocket D with a buckle E. This buckle E is preferably of the construction shown—that is to say, it comprises a body-plate *m*, connected to the face 5 of the pad-body and provided at its ends with angular ears *n*, which terminate in lateral inwardly-directed branches *p*, (see Fig. 3,) and a tongue *q*, which has a finger portion *r*, an angular serrated or toothed portion *s* at the 10 forward end of the finger portion, and tubular portions *t* at the opposite ends of the toothed portion *s*, which loosely receive the branches *p* of the body-plate, so as to enable the tongue to swing thereon. The pocket D 15 is designed to receive the end portion of the belt B opposite to that carrying the tab *b*, as better shown in Figs. 1 and 2 of the drawings, while the buckle E is designed to fasten such end portion of the belt to the said body.

20 In virtue of the employment of the pocket D and buckle E the truss may be put on the market with the belt B sufficiently long for a person of very large girth and may be quickly and easily made to fit a much smaller 25 person. To do this, it is simply necessary to open the buckle E and draw the end of the belt out of the pocket D, move it along until it is made short enough for the person being fitted, then cut off the surplus and replace the 30 free end in the pocket, after the manner illustrated, and close the buckle, so as to fasten it to the pad-body. When the rough-cut end of the belt is thus placed in the pocket, said pocket will prevent it from detracting from the 35 finish of the truss and will also prevent it from curling and pressing the clothing of the wearer of the truss outwardly. Furthermore, the pocket will render it entirely unnecessary to bind the cut end of the belt, 40 since, as above stated, it entirely hides the same from view.

It is clear from the foregoing that our improved construction of truss renders it entirely unnecessary for a retail dealer to incur 45 the expense incident to installing and maintaining a large stock of trusses with belts of various lengths in order to be able to fit persons of different sizes.

We prefer to employ the specific buckle E 50 shown and described, because the same does not entail the formation of holes in the belt and offers but a slight projection from the face of the pad-holding body. However, the said buckle in itself forms no part of our invention and may be replaced when desired by any other buckle suitable for use in a truss.

In Fig. 6 of the drawings we have shown a double truss—that is to say, one having two pads—embodying our invention. In this construction the pad-holding body A' is provided with two female clasp members *e'*, similar to the member *e* shown in Figs. 1 and 2, and the belt B' is provided at its opposite ends with tabs *b'* *b''*, having two male clasp members *a'*, 65 similar to that shown in Figs. 1 and 2. The tab *b''* of the belt is, however, of a peculiar

construction in that it is provided with a pocket D' and a buckle E', similar to those with which the pad-body A' is provided, as shown in Figs. 1 to 4.

The modified construction illustrated in Fig. 6 permits of the truss-belt being shortened in the same manner and quite as easily as does the construction shown in Figs. 1 to 5.

It is obvious that the construction shown 75 in Fig. 6 may be embodied in a single truss. It is preferable, however, to use the different constructions shown for the single truss and double truss, respectively. It is also apparent that the position of the holding-buckle 80 may be changed to suit the wishes of the trade.

We are well aware that it is old in harness to provide a covering or pocket in proximity to a buckle, the said covering or pocket being 85 designed to receive the loose end of a strap after the same is passed through the buckle; also, that it is old in trusses to combine a pad or pad-holding body, a strap permanently connected thereto, and a second 90 strap adjustably connected at one end to the first-named strap through the medium of a buckle and detachably connected at its opposite end to the pad or pad-holding body. We 95 therefore make no claim to these constructions.

What we claim, and desire to secure by Letters Patent, is—

1. The truss described comprising a pad-holding body, a pocket connected with the 100 pad-body, a buckle also connected with the pad-body and arranged in advance of the mouth of the pocket, the belt extending through and adjustably connected to the buckle and having one of its ends removably 105 arranged in the pocket and its other end free, and suitable means for detachably connecting the said free end of the belt with the pad-body, substantially as specified.

2. In a truss, a pad-holding body, a pocket 110 arranged on and connected to the face of the pad-holding body and having an open end or mouth contiguous to one end of the same, a buckle arranged on the face of the pad-holding body in advance of the mouth of the 115 pocket, a belt extending through and adjustably connected to the buckle and having one of its ends removably arranged in the pocket, and its other end free, and suitable means for detachably connecting the said free end of 120 the belt with the pad-body, substantially as specified.

3. In a truss, a pad-holding body having a covering of leather or other material, on its 125 face forming a pocket having an open end or mouth contiguous to one end of the pad-holding body, a buckle arranged on the face of the pad-holding body in advance of the mouth of the pocket, a belt extending through and adjustably connected to the buckle and having one of its ends removably arranged in the 130 pocket, and its other end free, and suitable

means for detachably connecting the said free end of the belt with the pad-holding body, substantially as specified.

4. In a truss, a pad-holding body, a female clasp member having a central depressed portion and a marginal flange bearing against the face of the pad-holding body and also having a slot between said depressed portion and flange, a connecting device extending through the depressed portion of said clasp member and the pad-holding body, and a belt connected at one end with the pad-holding body and having a male clasp member at its opposite end provided with a T-shaped tongue adapted to enter the slot of the female member, substantially as specified.

5. In a truss, a pad-holding body, a female clasp member having a central depressed portion and a marginal flange bearing against the face of the pad-holding body and also having slots between said depressed portion and

flange, a connecting device extending through the depressed portion of said clasp member and the pad-holding body, a belt connected at one end with the pad-holding body and having a male clasp member at its opposite end provided with a T-shaped tongue adapted to enter one of the slots of the female member, and a strap connected at one end to the belt and having a male clasp member at its opposite end provided with a T-shaped tongue adapted to enter the other slot of the female member, substantially as specified. 25 30 35

In testimony whereof we have hereunto set our hands in presence of two subscribing witnesses.
